ABSTRACT OF THE DISCLOSURE

In a gas actuated feed system which has a liquid or a liquid with solids therein stored in a tank, an oscillation damping porous metal plug is provided in the end of the supply tube leading to a vaporizer, attached to a nozzle. The nozzle end of the vaporizer is heated and radiation fins are located on the vaporizer to provide the proper temperature gradient along the vaporizer. An enlarged liquid supply hole is provided near the end of the vaporizer. Blind holes are provided adjacent the liquid supply holes in the vaporizer to hold excess liquid during oscillations of the liquid in the liquid supply tube.

Background of the invention

Various systems have been used for metering flow in the vapor feed systems used in magnetoplasma dynamic thrusters. The most common of these requires the heating of the entire storage container to a temperature high enough so that the vapor pressure causes the discharge orifice to choke. Under these conditions, the flow-rate is proportional to vapor pressure which in turn is a function of the liquid temperature.

Two major disadvantages of this system are that the vapor pressure is very sensitive to temperature and for long periods in space the electrical power required is excessive.

Another method is to feed the liquid by positive displacement such as by extending nested bellows. This method suffers from the problem of temperature and pressure variations which cause the system to be unsteady and inaccurate due to vapor pressure variations due to volume displacement of the bellows due to these variations.

Summary of the invention

According to this invention a gas-actuated feed system is used. The major difficulty with a gas-actuated feed system is the stabilization of the vapor flowing from the sonic nozzle orifice due to the tendency of the liquid column to oscillate at a frequency of 1-10 cycles per second. The unique feature of this invention relates to the means of stabilization of the vapor flowing from the nozzle. This is accomplished by incorporating a porous plug in the inlet tube leading to the vaporizer, the provision of blind holes in the vaporizer parallel to the vaporizer holes and by the establishment of the proper temperature gradient in the vaporizer.

Brief description of the drawing

FIG. 1 is a schematic diagram of a gas-actuated vapor feed system according to the invention;

FIG. 2 is an enlarged view of the vaporizer unit of the device of FIG. 1;

FIG. 3 is a sectional view of the device of FIG. 2 along the line 3—3; and

FIG. 4 is an enlarged sectional view of the device of FIG. 2 along the line 4—4.

Description of the preferred embodiment

Reference is now made to FIG. 1 of the drawing which shows a liquid supply tank 10 having a heating

2

coil 12 surrounding the tank to melt any solid material in the tank. The power requirements for this coil are not as great as for the system described above. The tank may contain various liquids or mixtures of liquid and solid particles, but in use for which it was constructed the material 14 used is liquid lithium. The heating coil 12 may not be needed when no solid particles are in the liquid. A vaporizer shown schematically at 16 is connected to the tank 10 by means of a liquid feed tube 17. A porous metal plug 18 of a material such as tungsten is located in the end of tube 17 within the tank 10 for filtering and damping oscillations within the tube 17. A gas under pressure such as argon is supplied to the tank 10 through an inlet tube 22. A pressure regulator 24 and pressure gauge 25 are provided in the inlet tube 22. The pressure regulator may be either manual or automatic depending upon the particular use of the apparatus.

Since the porous plug 18 will not damp out all oscillations, a plurality of blind holes 27, shown in FIGS. 3 and 4, are provided in the vaporizer and are located around the supply holes 28.

The end of the vaporizer 16 is connected to the anode 29 of the dynamic thruster. The anode is heated by the discharge between cathode 30 and anode 29 and this heat is conducted to the vaporizer 16. If the vaporizer is used for other purposes, a separate heat source such as an electrical heating element, may be provided adjacent the end of the vaporizer 16.

Radiation fins 31 are spaced along the outer surface of the vaporizer 16 to establish a proper temperature gradient along its length. An enlarged passage 33 is provided in the vaporizer leading to the annular nozzle orifice 34 in anode 29.

The oscillations of the liquid column are stabilized by the strong temperature gradient, the large internal wall surface, in the vaporization region, and the porous plug in the tube inlet.

The vapor pressure above the liquid gas interface is further stabilized by means of the plurality of blind holes 27 which surround the liquid supply holes 28. The volume of holes 27 is large compared to the volume of holes 28, so that during a period of oscillation of the vaporizing interface the excess vapor condenses in the blind holes 27 to supply any deficiency of vapor from supply holes 28.

If the oscillations are such that an excess amount of fluid enters the blind holes, though not shown, a return to the liquid supply may be provided from these holes.

There is thus provided a vapor feed system that does not have the disadvantages of prior art systems.

While a certain specific embodiment has been described, it is obvious that numerous changes may be made without departing from the general principles and scope of the invention.

I claim:

1. A gas-actuated vapor feed system comprising: a liquid supply container having vaporizable liquid therein; a vaporizer having a sonic nozzle connected at one end thereof; a supply tube having one end immersed in said liquid and the other end connected to said vaporizer at the end thereof opposite said nozzle; a porous metal plug in the end of said supply tube immersed in the liquid; said vaporizer having at least one liquid passage therethrough; an enlarged liquid passage in said vaporizer at the end adjacent said nozzle; means for heating the end of said vaporizer adjacent said nozzle whereby a temperature gradient is provided along the length of said vaporizer; means for supplying a gas under pressure to said supply container whereby liquid is supplied to said vaporizer; means for controlling the pressure of said gas to thereby control the flow of said liquid.

2. The device as recited in claim 1 wherein a plurality of blind holes are provided in the vaporizer surrounding the liquid passage.

3. The device as recited in claim 2 including a dynamic thruster having a cathode and an anode surrounding said cathode, said nozzle being an annular nozzle located within said anode whereby said heating means is said anode which is heated due to the discharge between the cathode and said anode.

4. The device as recited in claim 3 including a plurality of radiation fins surrounding said vaporizer for aiding

in the establishment of the temperature gradient along the length of the vaporizer.
